(57) **CLAIM**

The ornamental design for a bracket with removable support members as shown and described.

DESCRIPTION

FIG. 1 is a front perspective view of the bracket with removable support members of the present invention; FIG. 2 is rear isometric view thereof; FIG. 3 is yet another front view thereof; FIG. 4 a rear view thereof; FIG. 5 is a front view thereof; FIG. 6 is a right-side view thereof; FIG. 7 is a left-side view thereof; FIG. 8 is a top plan view thereof; and, FIG. 9 is a bottom plan view thereof.

The broken lines represent boundaries to disclaim the interior of the removable elongated member, the removable pin, and one of the removable elongated members.

1 Claim, 9 Drawing Sheets
